(57) **CLAIM**

The ornamental design of a ceiling hanging LED light fixture, as shown and described.

DESCRIPTION

FIG. 1 is a perspective view of a design of a ceiling hanging LED light fixture as viewed looking up;

FIG. 2 is a front view of the light fixture of FIG. 1;

FIG. 3 is a rear view of the light fixture of FIG. 1;

FIG. 4 is a right end view of the light fixture of FIG. 1;

FIG. 5 is a left end view of the light fixture of FIG. 1; and, FIG. 6 is a bottom view of the light fixture of FIG. 1 as viewed looking straight up.

The top surface of the light fixture, which attaches to the ceiling, is not shown and forms no part of the claimed design.
